UNITED STATES PATENT OFFICE.

GEORGES BERTHELEMY PERTUISET, OF GENEVA, SWITZERLAND.

BISCUIT-CUTTING MACHINE.

Application filed April 15, 1920. Serial No. 374,198.

(GRANTED UNDER THE PROVISIONS OF THE ACT OF MARCH 3, 1921, 41 STAT. L., 1313.)

To all whom it may concern:

Be it known that I, GEORGES BARTHELEMY PERTUISET, citizen of Switzerland, residing at Geneva, Canton of Geneva, in the Confederation of Switzerland, have invented certain new and useful Improvements in Biscuit-Cutting Machines (for which I filed an application for Letters Patent in Switzerland on April 7, 1919, Patent No. 85,385),

10 of which the following is a specification.

The object of the present invention is the provision of a biscuit cutting machine, in which a knife mounted slidably within vertical guides is attached to a motor driven crankshaft, so as to have a vertical reciprocating movement; an eccentric being mounted on the same shaft and attached by means of a connecting rod to a pawl and ratchet gear, which operates a ratchet wheel for moving a slide in a longitudinal direction with regard to the machine, said slide holding the biscuits and presenting the same to the knife.

The annexed drawing represents as an example one working form of this invention.

Fig. 1 is a side elevation.

Fig. 2 a top view, partly in section.

Fig. 3 is an end view thereof.

Figs. 4, 5 and 6 represent in horizontal 30 projections and on a larger scale than in Figs. 1 to 3 three different forms of a knife.

Fig. 7, likewise on a larger scale, is a partial perspective view of a detail.

The machine as shown in Figs. 1 to 3 and 7 consists of a bedplate α supported by feet α' and carrying a frame α^2 secured thereto. Said frame is provided with two vertical guides α^3 for a knife b . At the upper part of the frame α^2 there is mounted

40 within bearing α^4 a crank shaft c attached by means of a connecting rod c' to the top end of the knife b . A pinion c^2 is keyed to the one end of shaft c and meshes with a pinion c^3 mounted on the same shaft with a pulley c^4 operated from a motor not shown in the drawing. The crank shaft c carries at its other end a disc c^5 with a crank pin c^6 the eccentricity of which pin may be regulated by means of a screw c^7 provided

45 with a milled knob for handling. The crank pin c^6 is connected by means of a rod d to an oscillating lever fitted with pawls d^2, d^3 which operate a ratchet wheel d'

keyed to a journaled shaft e , supported by the bed plate. Keyed to this shaft there is 55 a pinion f which meshes with a rack f' fixed to the under side of a slide g for imparting to this slide a longitudinal movement relatively to the machine. The pinion f is mounted on a hub adapted to slide on the 60 shaft e for a distance controlled by means of a pin f^2 fast to said shaft and engaging a slot f^2 provided within one of the extended hubs of the pinion f , the other extended hub of said pinion being attached by means of 65 a forked lever f^4 to a rod provided with a handle f^5 suitably arranged on the bedplate so as to be easily moved by an operator. A catch h having a bevel edge and connected to a rod h' fitted with a spring h^2 is adapted 70 to bear frictionally against the adjacent hub on which the pinion f is mounted, thereby tending to maintain the said pinion in that position in which it is not in mesh with the rack, thus assisting in releasing the pinion 75 when it is desired to stop the slide.

A slide g carries another plate g' made for instance of sheet metal and which is removably connected thereto. A bracket i (Fig. 7) is secured to the bedplate α and lies above said two plates g and g' . After being kneaded the dough which is to be cut into slices is placed in grooves in this bracket i . This bracket i is provided at its fore end with a cleft i^2 forming an aperture 80 for receiving the knife blade b . The elongated pieces j of kneaded dough are placed on said bracket i and within the grooves or hollows i' which may be provided with flutings. The dough is held in place by 85 rollers k which are journaled at the end of arms k' and pressed downwards by means of springs k^2 . The pieces of dough j are pushed forwardly by means of pistons or plungers. These pistons or plungers l are 90 each mounted on a rod l^2 which passes through and is journaled in a bearing provided therefor in a support l' . The support l' is connected to and moves with the plate g . On each rod l^2 and extending between 95 its plunger or piston l and the support l' there is a spring l^3 by which the plunger is caused to bear yieldingly against the dough j in moving the same along in the groove in the bracket i . The pistons l are made 100 to fit in the grooves in the bracket i and the

support l' is adapted to bridge the bracket i so that the latter may pass through the same as the plate and dough advance.

The working of the machine is as follows:

- 5 The movable plate g is in its starting position and in order to prevent any anticipated starting, the pinion f is thrown out of gear with the rack f' . The bracket i provided with longitudinal hollows i' corresponding to the forms of the pieces of kneaded dough which are to be cut up is arranged on the bed plate a in such a way that the cleft i'' at its fore part is within the plane wherein the knife reciprocates, and
- 10 one or more pieces of the dough depending upon the number of hollows i' in said bracket i are placed therein, and kept in position by the rollers k and the pistons l . By means of the screw c^1 the eccentricity of
- 15 the crank pin c^6 of disc c^5 is regulated and this regulation controls the extent of each movement of the ratchet wheel d' and pinion f and consequently the advance of the rack f' for each alternating movement of
- 20 the knife blade b , thus fixing the thickness of the slices of dough to be cut off. After this regulation, the pinion f is thrown into gear with the rack by means of the handle f^3 and the machine is started by means of
- 25 the pulley c^4 . This latter when turning will move shaft c by means of the gears c^2 , c^3 , which shaft through the rod c' imparts to the knife b an alternating movement upwards and downwards. This move-
- 30 ment takes place at a time when the slide g is stationary so that the pieces of dough will be cut into slices of the desired thickness, whereupon the slices will be dropped on the fore part of plate g' of sheet metal
- 35 where the slices may be collected for the
- 40

purpose of baking the same in the oven. The plate g' as hereinbefore described is removable from the slide g and hence after the biscuits are cut and delivered thereto may be removed and transferred with the biscuits thereon to an oven for baking the biscuits.

The shape of these pieces of dough may be varied and be different from that shown in the drawing, therefore also the bracket i is made interchangeable and the hollows may be shaped at will. Also the horizontal projection of the knife may be in any form to suit the shape which it is desired to give to the faces of the biscuits.

The Figures 4, 5 and 6 show three working forms of the knife b in horizontal projection.

I claim as my invention:

In a biscuit cutting machine, a frame, a dough holder formed in the frame and having slots therein for receiving the dough, a reciprocating slide, plungers yieldingly mounted on the said slide and lying within the said recesses in the dough holders to move the dough when the slide is moved, a knife, a crank shaft by which the knife is operated, an auxiliary shaft, means for operating the auxiliary shaft from the said crank shaft, a gear slidably mounted on the auxiliary shaft, a rack on the said reciprocating slide, and means for sliding the said gear into and out of mesh with the said rack.

In testimony whereof I affix my signature in presence of two witnesses.

GEORGES BARTHELEMY PERTUISET.
